UNITED STATES PATENT OFFICE.

BERTHA C. SELIGMAN, OF PROVIDENCE, RHODE ISLAND, ASSIGNOR TO SEEKONK LACE COMPANY, A CORPORATION OF RHODE ISLAND.

DESIGN FOR LACE.

Application filed January 27, 1926. Serial No. 16,287. Term of patent 3½ years.

To all whom it may concern:

Be it known that I, BERTHA C. SELIGMAN, a citizen of the United States, residing at Providence, in the county of Providence and State of Rhode Island, have invented a certain new, original, and ornamental Design for Lace, of which the following is a specification.

In the accompanying drawings which form a part of this specification the figure is a front elevation of lace embodying my invention.

I claim:—

The ornamental design for lace, as shown.

BERTHA C. SELIGMAN.
